United States Patent Office

Des. 183,596
Patented Sept. 30, 1958

183,596

FOOD GRINDER

Charles R. Bowland, Spring Valley, Ill.

Application August 21, 1957, Serial No. 47,464

Term of patent 14 years

(Cl. D89—1)

Fig. 1 is a side view of the food grinder of the invention, and

Fig. 2 is a top view of the food grinder.

The apertures in the grinding disc shown fragmentarily in Fig. 2 are continued throughout the said disc.

I claim:

The ornamental design for a food grinder, as shown and described.
